UNITED STATES PATENT OFFICE.

JESSE G. VINCENT, OF DETROIT, MICHIGAN, ASSIGNOR TO PACKARD MOTOR CAR COMPANY, OF DETROIT, MICHIGAN; A CORPORATION OF MICHIGAN.

HYDROCARBON-MOTOR.

1,352,487.

Specification of Letters Patent. Patented Sept. 14, 1920.

Original application filed October 4, 1916, Serial No. 123,716. Divided and this application filed January 16, 1919. Serial No. 271,361.

To all whom it may concern:

Be it known that I, JESSE G. VINCENT, a citizen of the United States, and resident of Detroit, Wayne county, State of Michigan, have invented certain new and useful improvements in Hydrocarbon-Motors, of which the following is a specification.

This application is a division of application Serial No. 123,716, Jesse G. Vincent, hydrocarbon motors.

This invention relates to hydrocarbon motors and in the illustrative form in which it is herein shown, the invention is applied to a hydrocarbon motor of the multi-cylinder V type.

One of the objects of the invention is to provide a hydrocarbon motor with a cam shaft casing construction of novel and efficient form and one that may be conveniently and accurately manufactured.

Another object of the invention is to provide an efficient lubricating system for the cam shaft and valve operating mechanism of a hydrocarbon motor.

Another object of the invention is to improve the various coöperating parts of a hydrocarbon motor and to provide certain and efficient means for lubricating the moving parts.

Other objects of the invention will appear from the following description taken in connection with the drawings which form a part hereof, and in which:

Figure 1 is partly a front end view and partly a vertical transverse section of the motor.

Fig. 2 is a longitudinal sectional view, with parts shown in elevation, of the motor shown in Fig. 1, the section being taken through the center line of one of the blocks of cylinders;

Fig. 3 is a plan view of the rear part of one of the cam shaft casings, together with the contiguous part of the gear casing arranged at one end of the motor, some of the detachable covers of the cam shaft casing being removed;

Fig. 4 is a transverse section on the line 4-4 of Fig. 2;

Fig. 5 is an enlarged detail view of a cam shaft and valve operating mechanism.

Referring to the drawings, 10 represents the crank case of a hydrocarbon motor, having supporting arms 11 and a lower part or underneath cover 12. The latter forms

an oil well into which the oil from the various bearings of the motor drains and from which it is drawn and re-circulated. A pump for this purpose is shown at 13 in Fig. 1, the oil being drawn from the bottom of the crank case where it settles through the screen 14, and pumped through a conduit 15 in which there is a pressure regulating valve 16, to a screen 17 and the chamber 18 surrounding the same. From the chamber 18 the oil is led under pressure through pipes 19 and 20 to the various bearings of the motor. Said bearings will be hereinafter further described.

Cylinder blocks 21 are shown as formed separately from the crank case and detachably secured thereto. An engine of four cylinder blocks 21 is shown in the illustrative form of the invention herein, each block comprising three cylinders, two blocks being arranged with their cylinders in line and the two pairs of blocks being in V relation. Thus a 12 cylinder V type motor is illustrated.

The cylinder blocks 21 are water jacketed as at 22 and suitable inlets 23 and outlets 24 are provided. Each of the cylinders has an inlet port 25 and an outlet port 26 controlled by puppet valves 27 and 28 respectively. Springs 29 maintain these valves yieldingly in closed position. There is a spark plug 30 for each of the cylinders.

A carbureter 31 is preferably mounted in the space between the cylinders and branched intake headers 32, one for the cylinders on one side of the motor and another for the cylinders on the other side of the motor, connect the carbureter with the various intake ports of the cylinders. Suitable exhaust pipes 33 are connected with the exhaust ports of the motor.

Mounted in the main bearings of the crank case is a crank shaft 36. In the form shown this crank shaft has similar disks or cheeks 37, all of which are connected together by the crank pin and main bearing parts of the crank shaft.

The entire gear casing 58 is substantially of V form, the lower part of it extending down around the gear 55, and the upper part being in the form of two branches extending diagonally upward adjacent to but separated from the rear ends of the cylinder blocks. The upper part of each of these branches of the gear casing is formed by a detachable

cap 64, which as shown particularly in Fig. 2 is provided with an oil filler spout 65. Thus the oil in the crank case may be brought to the proper level by introducing oil through the spout 65, where it will enter the gear casing 58 and run down into the crank case.

In the motor herein shown, the cam shaft and operating mechanism for the valves 27 and 28 are in the form of a detachable unit 10 for each of the two pairs of cylinder blocks. Each such unit comprises a tubular cam shaft casing 66 which extends lengthwise of the motor and which is mounted on top of and connects the two aligned cylinder blocks. This casing is divided into several compartments 67, 68 and 69, by bearings 70, 71 and 72 for cam shaft 73. A supplementary bearing 72' may be provided as shown in each of the compartments 67 and 68. The cams 74 formed 15 on the cam shaft 73 are all arranged in the two main compartments 67 and 68 and the front end of the cam shaft extends through the front bearing 72 and into the end compartment 69. This end compartment 69 is 20 very small compared with the other compartments and is formed largely by a cap 69' screwed on to the end of the casing. It is supplied with oil under pressure by a pipe 20' which is a continuation of the pipe 30 shown in Fig. 1. Any other equivalent means may be used to supply oil under pressure to this compartment.

The cam shaft 73 is drilled out to make it hollow and oil leads 75 are provided from 35 its interior to each of the bearings 70, 71 and 72. The rear end of the cam shaft is closed but the front end is open to the compartment 69 so that the oil under pressure in that compartment passes into the cam shaft and through the oil leads 75 to the bearings above referred to. The oil flowing from these bearings accumulates in the compartments 67 and 68, which are interconnected by a channel 76, similar channels 40 76' being provided in the bearings 72' and from the rear compartment 67 it overflows through the openings 77 Fig. 4 through the bearing 70 into the gear casing 58 and down into the crank case where it is collected and 45 again circulated as herein above described.

The compartments 67 and 68 above referred to are formed with top openings 78 above the various cams on the cam shaft 73. Each of these openings has a cover 79 55 and between the cover and the casing is pivotally supported one or more rock shafts 80. Each of these rock shafts 80 is drilled out as shown for instance in Figs. 1 and 5 and has an oil lead 81 leading from its interior to its bearing surface. An oil cup 82 is also formed in the upper part of the rock shaft and a downwardly extending lug 83 on the cover 79 directly over the cup 82 causes some of the oil splashed up onto the 60 cover 79 to drip into the cup. This oil then 65

passes into the rock shaft 80 and to its bearing surface.

Each rock shaft has an arm 84 upon which is a roller 85 in contact with one of the cams 74 of the cam shaft, and the end of the rock 70 shaft 80 that extends outside of the cam shaft casing is provided with an arm 86 having an adjustable plunger 87 in contact with the stem of one of the valves 27 and 28.

From the above description it will be seen 75 that the cam shaft casing 66, the cam shaft, and all of the rock shafts and other operating parts may be assembled before the unit is placed on the motor. It may then be attached to the tops of the cylinder blocks by 80 the lugs 88 and bolts 89. It may also be secured to the gear casing 58 by the cap 64 which has a part 90 co-operating with a part 91 on the gear casing, which parts are arranged to clamp the tubular casing 66 85 between them. Endwise movement of the tubular casing 66 relative to the gear casing 58 is prevented by reason of the flanges 92 on the tubular casing. By this connection of casings and cylinder blocks a very strong and 90 rigid construction is obtained.

The spur gear 55 on the crank shaft has been herein above referred to. This gear forms one of a train of gears between the crank shaft and an auxiliary shaft 93 which, 95 in the form of the invention shown, is mounted directly above and parallel to the crank shaft. This auxiliary shaft 93 is mounted in bearings 94 and 95 in the gear casing 58 and is shown connected with a 100 generator 97 for supplying electric current to the spark plugs of the motor. The generator is mounted on a bracket 98 arranged between the cylinder blocks.

From the auxiliary shaft 93 there are two 105 trains of gears which extend in opposite direction and are arranged to operate the two cam shaft at one-half crank shaft speed. Of these trains of gears, only several gears of one of the trains are herein shown, including a gear 107 meshing with an idler gear 109, which meshes with a gear 110 secured to the rear end of one of the cam shafts 73. A similar idler gear 109 meshes with the gear 108 and itself meshes with a 110 gear 110 on the other cam shaft 73. It will be understood that the gear 106 has just half as many teeth as each of the gears 110, so that the cam shaft 73 will operate at one-half crank shaft speed, for operating the 115 motor on the four stroke cycle.

All of the gears above referred to are shown as of the straight tooth spur type but it will be understood that other equivalent gears may be used for the same purpose. 120

Referring to the arrangement of the cam shaft casing and the gear casing, it will be seen that the former may be removed by removing the bolts 89 and the caps 64. Also the upper part 61 of the gear casing may be 125

detached and this part of the casing will carry with it the gears 109 and 110 as well as the upper parts of the bearings of the gears 106, 107 and 108.

5 It will be understood that various changes and modifications may be made without departing from the spirit or scope of the invention as defined by the claims.

Having thus described my invention, what 10 I claim and desire to secure by Letters Patent is:—

1. In a hydrocarbon motor, in combination, a casing, a cam shaft therein, a rock shaft mounted in the casing above the cam shaft, said rock shaft being hollow and having an exposed upper opening, and a downwardly extending lug on the wall of said casing over said opening for the purpose described.

2. In a hydrocarbon motor, in combination, a casing having an opening therein and a cam for said opening, a cam shaft in said casing, a rock shaft mounted in the casing above the cam shaft, said rock shaft 25 being hollow and having an exposed upper

opening, and a downwardly extending lug on said cover over said cam shaft opening for the purpose described.

3. In a hydrocarbon motor, in combination, a casing adapted to receive lubricating oil, a rock shaft therein, said rock shaft being hollow and having an exposed upper opening, means in said casing for splashing the oil against the wall thereof and a downwardly extending lug on the wall of said casing over said opening to guide certain of the splashed oil into said hollow rock shaft.

4. In a hydrocarbon motor, in combination, a casing adapted to receive lubricating oil and having an upper opening therein, a cam for said opening, a rock shaft in said casing, said rock shaft being hollow and having an exposed upper opening, means in said casing for splashing the oil against the wall and cover thereof and a downwardly extending lug on said cover over said rock shaft opening to guide certain of the splashed oil into said hollow rock shaft.

In testimony whereof I affix my signature.

JESSE G. VINCENT.
